(57) **CLAIM**

The ornamental design for an apheresis device as shown and described.

DESCRIPTION

FIG. 1 is a front perspective view of an apheresis device; FIG. 2 is a rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines in the drawings illustrate portions of the apheresis device, which form no part of the claimed design. The dot dash lines define the bounds of the claimed design and form no part thereof.

1 Claim, 8 Drawing Sheets
